UNITED STATES PATENT OFFICE.

LEONARD M. SULLIVAN, OF GIRARD, KANSAS.

GRAVE-MARKER.

1,364,902.

Specification of Letters Patent. Patented Jan. 11, 1921.

Application filed September 13, 1920. Serial No. 409,881.

To all whom it may concern:

Be it known that I, LEONARD M. SULLIVAN, a citizen of the United States, residing at Girard, in the county of Crawford and State of Kansas, have invented certain new and useful Improvements in Grave-Markers, of which the following is a specification, reference being had therein to the accompanying drawings.

- 10 This invention relates to grave markers and it has for its object to provide a device of this nature adapted to be formed of sheet metal and arranged to receive and retain an identification card in such manner that 15 the latter will be firmly held in place and will be protected from the weather. It is designed to provide an article of the character indicated which may be manufactured at a comparatively small cost, may be easily 20 and quickly placed in position and will last for years without any expense for upkeep.

Further advantages and objects of the invention will be set forth in the detailed description which follows.

- 25 In the accompanying drawing—

Figure 1 is a front elevation of a grave marker constructed in accordance with the invention.

Fig. 2 is a rear elevation thereof.

- 30 Fig. 3 is a central, horizontal sectional view.

Fig. 4 is a vertical sectional view upon line 4—4 of Fig. 2.

Fig. 5 is a fragmentary plan view, and

- 35 Fig. 6 is a detailed view of a cross adapted to be mounted upon the top of the grave marker.

Like numerals designate corresponding parts in all of the figures of the drawing.

- 40 Referring to the drawing 5 designates the back plate and 6 the front plate, these plates complementally constituting the body portion of the grave marker. These plates are preferably formed of sheet metal and are 45 hingedly connected to each other at 7. The front plate 6 is provided with an opening 8 and the metal about the edge of said opening is bent to form an offset lip 9 within which a glass cover plate 10 and an identification card 11 are received. The back plate

- 50 5 is preferably struck inwardly to form ribs 12 which act to engage the card and press it firmly against the glass 10 and lip 9. The front plate 6 is provided with a tongue 13 55 that is adapted to be bent over the rear plate

after the identification card has been placed in position. The upper edge of the front plate is provided with a rearwardly extending flange 14 which overlies the upper edge of the rear plate and prevents the entry of 60 rain or snow between the plates. A supporting stake 15 which is preferably of channel formation is riveted to the back plate. The lower end of this stake is pointed to facilitate its ready entry into the ground and the 65 provision of the channel ribs 16 along the edges of the stake not only lend rigidity and strength to the stake but aid in giving the stake a firm hold in the ground.

The stake is preferably widened at its upper end and the flanges 16 at the widened part are bent inwardly as indicated at 16^a to form a channel 17 for the reception of the correspondingly shaped portion 18 of a cross 19 that is intended to be mounted 75 upon the top of the grave marker.

The lettering shown upon the card in Fig. 1 is merely indicative of the use of the device. Any suitable lettering may be employed. While this grave marker is of general application it is particularly useful for marking the graves of soldiers and when employed for that purpose the card may be used to carry indicia showing the rank, arm of the service (whether infantry, cavalry, etc.) and the battle or battles in which the deceased participated or other like information.

It is understood that this invention is not limited to the precise construction set forth 90 but that it includes within its purview whatever changes fairly come within either the terms or spirit of the appended claims.

Having described my invention, what I claim is:

1. A grave marker comprising front and back plates, means for connecting said plates to hinge together at one end, a horizontal flange upon the upper edge of one of said plates which moves into position to overlap 100 the upper edge of the other of said plates when said plates are brought together and secured by said retaining means, a retaining means at the opposite end, an offset lip upon the front plate surrounding a sight opening 105 therein said lip being adapted to receive a glass plate and an identification card and a ground engaging stake fixed to the back plate.

2. A structure as recited in claim 1 where- 110

in the ground engaging stake is of channel formation and a cross adapted to enter the channel formed by said stake.

3. In a grave marker a front plate having
5 a sight opening therein and an offset lip
surrounding said opening, a back plate to
which the front plate is hinged at one end,
means for securing the free ends of the
10 plates together, a glass plate and a card
adapted to fit within the offset lip, ribs upon
the back plate projecting toward the front
plate to engage said card, a flange upon the
front plate overlapping the upper edge of
the back plate when the free ends of the

plates are secured together to prevent the 15
entry of the weather and a ground engaging
stake of channel formation riveted to the
back plate.

4. A structure as recited in claim 3 where-
in said stake is increased in width adjacent 20
its upper end and its edges are inturned and
a cross having its lower portion of channel
formation to engage in the channel formed
by the upper part of the stake.

In testimony whereof I hereunto affix my 25
signature.

LEONARD M. SULLIVAN.
